UNITED STATES PATENT OFFICE.

J BIRCHARD GREEN, OF CHICAGO, ILLINOIS, ASSIGNOR TO CHICAGO STEEL & WIRE COMPANY, OF CHICAGO, ILLINOIS, A CORPORATION OF ILLINOIS.

REEL.

1,264,918.

Specification of Letters Patent.

Patented May 7, 1918.

Application filed June 7, 1915. Serial No. 32,490.

To all whom it may concern:

Be it known that I, J BIRCHARD GREEN, a citizen of the United States of America, and resident of 1620 East 55th St., Chicago, Illinois, where I am now living and receive mail, have invented a certain new and useful Improvement in Reels, of which the following is a specification.

My invention relates to rotary reels for feeding or delivering wire or the like to machines, or for other purposes. For example, reels of the kind to which my invention relates are employed on stapling machines to feed the wire to the staplers.

Generally stated, the object of my invention is to provide an improved and a comparatively simple and inexpensive reel which may become a part of any machine upon which it is used, and which will readily and conveniently receive a coil or winding of wire, or a winding of any other suitable material, thereby enabling the manufacturer of the wire, or other material, to supply the same without the necessity of providing a reel for each coil or winding, thus reducing the expense of transportation and the general cost to the consumer or user.

A special object is to provide a reel of this kind which will operate in conjunction with the different kinds of friction brake devices which are now employed on stapling and other machines.

Another object is to provide a novel and simple construction which will enable the manufacturer to supply the wire with a wood filler for each coil or winding, and with means for holding the wire in place on said fillers during transportation, and so that each filler will serve in effect as a part of the reel during the unwinding of the wire.

It is also an object to provide certain details and features of construction and combinations tending to increase the general efficiency and desirability of a reel and windings or coils of wire therefor of this particular character.

In the accompanying drawings—

Figure 1 is an end elevation of a reel embodying the principles of my invention, showing a winding or coil of wire in position thereon.

Fig. 2 is a side elevation of said reel and coil of wire.

Fig. 3 is a vertical section on line 3--3 in Fig. 1.

Fig. 4 is a detail horizontal section on line 4--4 in Fig. 3.

Fig. 5 is a perspective of one of the windings or coils of wire with its core or filler of wood, which latter is used in preparing the winding or coil, is shipped with the wire, and finally facilitates the insertion of the winding in the reel and becomes a part of the latter, temporarily, each filler being removed from the reel after the load of wire has been unwound therefrom, as will hereinafter more fully appear.

Fig. 6 is a side elevation of another form of spool or filler for the coils.

As thus illustrated, my invention comprises a tubular hub A consisting of a section of pipe which is externally threaded at opposite ends thereof. The flanges B and C are preferably in the form of spiders, may be of aluminum or other suitable metal or material, and are preferably alike to render it unnecessary to manufacture more than one form in the production of a reel of this kind. The flange C comprises, therefore, an annular periphery 1 and radial spokes 2, 80 said spokes being provided with grooves 3 extending lengthwise thereof. This flange C is screwed upon one end of the hub A, the screw threads 4 on said hub extending some distance inside of the inner surface of the 85 flange, for the purpose hereinafter explained. The threads 5 of the flange B, formed on the other end portion of said hub extend no farther than is necessary to tightly receive this flange. A cylindric wood filler D forms 90 a core for the winding or coil of wire E, and is provided with a bore 6 to receive the said hub of the reel. This filler D is tightly clamped between the flanges B and C, inasmuch as the threads 4 extend within the 95 filler, thereby insuring removal of only the flange C whenever the two flanges are relatively rotated to permit removal of an unloaded filler. Being tightly clamped in this manner, the filler D rotates with the reel, 100 and in effect forms a part thereof, being simply an enlargement of the hub.

The method of use is as follows: The windings or coils of wire are produced and shipped in the form shown in Fig. 5, binding pieces of wire F being employed for holding the wire in place or against unwinding during transportation. The filler D is rotated on a suitable machine to wind the wire thereon. These pieces of wire F 110

are removed when the user is ready to unwind the wire. In certain machines, as is well known, brake shoes are provided for frictionally engaging the smooth periphery 5 of the reel, thereby properly retarding the rotation of the reel during the unwinding of the wire. In other machines different brake devices are employed, these being of the well known form in which a plurality of springy 10 arms engage the sides of the reel. With the construction shown and described, involving flanges which are made with openings to reduce the weight thereof, it is necessary that these springy arms of the brake device 15 rotate with the reel, and hence the provision of the grooves 3 to receive the ends of said arms and thereby prevent the latter from slipping off and into the openings between the spokes. In this way, a very light and 20 simple reel is provided which becomes a permanent part of the machine upon which it is used, the only portion thereof which is not absolutely permanent being the core or filler D which is supplied with each winding of coil of wire. As these fillers D may 25 be made of wood or paper or other light sheet material, it follows that the cost thereof is very small, and that the expense of transportation is also very greatly reduced 30 as compared with the old system which involved the provision of a comparatively heavy reel or spool with each winding or coil. By my invention, therefore, it is possible to do away with the old spools or reels 35 which were furnished with each coil of wire, thus reducing the cost of manufacture and the expense of transportation, and to do this without interfering in any way with the ease and convenience with which the 40 coils are successively placed on the machine.

It will be understood, of course, that in actual use, and in accordance with the general practice, the stapling or other machines are provided with a spindle or axle which 45 passes through the axial bore 7 of the hub of the reel, whereby the latter is supported in position to rotate. Various means and devices, as is well known, are employed for supporting the friction brake devices in position to engage the reel and retard the rotation thereof during the unwinding of the wire.

As shown in Fig. 6, the filler G is formed with disks g, secured to the ends thereof to 55 hold the wire in place. This is desirable in some cases, especially with round wire. In some cases, it is also desirable to provide the filler D with a hole d for one of the fastening wires F, whereby the filler is prevented from dropping out during shipment.

The core D, of course, serves to space the two flanges apart, and when the removable flange C is screwed into position it bears 60 against the end of this core or support for the wire, so that said core D is compressed

between the two flanges. It is the frictional engagement, therefore, of the flange C with the end of the core D which prevents the removable flange from rotating on the hub A, and from working loose during the use of 70 the reel. It follows, therefore, that this element D must be strong and rigid to resist the endwise compression to which it is subjected between the two flanges, thereby to afford the frictional engagement with the 75 flange C which prevents this flange from becoming unscrewed.

It will be seen, of course, that the filler D serves as means for centering the wire or coil or winding in the reel before and also 80 after the removable flange is screwed upon the tube or otherwise adjusted into place. This not only facilitates the insertion of the coil or winding in the reel, but also prevents the coil or winding from becoming 85 reduced to an off-center or loose condition in the reel in the event that the removable flange works loose. If the removable flange should work loose, the coil or winding would still be held in a centered position in the 90 reel, and would remain concentric to the axis of the reel. Moreover, with the outer sides of the two flanges flush, or practically flush, the reel is adapted for use in various situations and in various ways which would 95 not be possible if projections extended outward from the sides thereof—that is to say, if the ends of the tube did not terminate or practically terminate in the two flanges. In the construction shown, the ends of the tube 100 do not extend beyond the flanges, and for certain situations and for certain kinds of work this is desirable and advantageous. With the construction shown and described, the bore of the filler D fits the tube or hub 105 A, so that when the winding and its filler are slipped into place, the coil is accurately centered in the reel, and the removable flange can then be screwed into place to compress the filler D, in the manner explained, 110 thereby to prevent compression of the wire, leaving the latter free to unwind easily, but at the same time frictionally holding the removable flange against unscrewing. The invention, however, is not limited to the exact 115 construction shown and described.

What I claim as my invention is:—

1. A reel for wire or the like, comprising a hub having provisions to mount the reel for rotation, and flanges for said hub, spaced 120 apart to hold the winding between them, having means for removing at least one of said flanges to permit loading of the reel, said flanges being of spider form and having spokes which are grooved to engage the ends 125 of a friction brake device.

2. A reel for wire or the like, comprising a hub having provisions to mount the reel for rotation, and flanges for said hub, spaced apart to hold the winding between them, 130

having means for removing at least one of said flanges to permit loading of the reel, said flanges being formed with spokes which are grooved to engage the ends of a friction brake device, and with peripheries which are adapted to engage the brake shoe of another type of friction brake device.

3. In combination, a reel for wire or the like, comprising a hub having provisions to mount the reel for rotation, and flanges for said hub, spaced apart to hold the winding between them, having means for rotatably removing at least one of said flanges to permit loading of the reel, said winding having a cylindric filler secured therein and upon which the wire is wound for shipment, and to facilitate placing of said winding on the reel, said filler having a bore fitting said hub to center the winding in the reel before and also after the removable flange is adjusted in place, and said filler serving frictionally to prevent relative rotation between said flanges.

4. In combination, a reel for wire or the like, comprising a hub having provisions to mount the reel for rotation, and flanges for said hub, spaced apart to hold the winding between them, having means for removing at least one of said flanges to permit loading of the reel, said winding having a wood filler fitting said hub to center the winding in the reel before and also after the removable flange is adjusted in place, said flanges having openings to expose portions of said filler and winding, and said means comprising screw threads on said hub, which threads extend within said filler to prevent one flange from being screwed too tight upon the hub, and to insure clamping of the filler by said flanges.

5. In combination, a reel for wire or the

like, comprising a hub having provisions to mount the reel for rotation, and flanges for said hub, spaced apart to hold the winding between them, having means for removing at least one of said flanges to permit loading of the reel, said hub consisting of a section of pipe screw threaded at opposite ends thereof, said winding having a filler formed with a bore to receive said hub, the screw threads at one end only of said hub extending within said filler, and said flanges being formed with means for cooperating with different kinds of brake devices, said flanges clamping the filler to prevent unwinding of the wire and the retarding action of said devices from unscrewing the removable flange.

6. A wire reel comprising a tube for rotation on a spindle inserted therein, a flange removably screwed onto one end of said tube, a flange fixed on the other end of said tube so that the tube terminates or practically terminates in the flanges and means for supporting and centering the wire in the reel before and also after the removable flange is screwed onto the tube, said means being compressed between the two flanges and of a diameter to engage the removable flange a distance from said tube, whereby said means serve to limit the screw adjustment of the removable flange toward the fixed flange, and so that said removable flange is held against unscrewing by frictional engagement with said means.

7. The structure of claim 6, as specified, said means comprising a cylindric block of wood with a bore fitting said tube.

Signed by me at Chicago, Illinois, this 27th day of May, 1915.

J BIRCHARD GREEN.
